UNITED STATES PATENT OFFICE.

HENRY LAFAYETTE BOOTH, OF FLORENCE, ALABAMA.

BED-BRACE.

No. 800,898.

Specification of Letters Patent.

Patented Oct. 3, 1905.

Application filed February 20, 1905. Serial No. 246,562.

To all whom it may concern:

Be it known that I, HENRY LAFAYETTE BOOTH, a citizen of the United States, residing at Florence, in the county of Lauderdale 5 and State of Alabama, have invented a new and useful Bed-Brace, of which the following is a full and exact specification.

My invention is an improved bed-brace adapted to be easily set up and adjusted or 10 disconnected without tools; and it consists in the construction and combination of devices hereinafter described and claimed, my object being to provide a cheap, simple, and efficient 15 brace to hold beds in square, protect the locks, and keep the slats and springs from falling.

In the accompanying drawings, Figure 1 is a top view of the brace before tightening. Fig. 2 is a top view of the brace after tightening. Fig. 3 is a view of the brace-lever made of 20 wood. Fig. 4 is a view of the brace-lever made of iron.

In the embodiment of the invention I provide a lever 1, with a staple or eye 2 and a notch 3, (two inches apart near its larger end.) 25 Brace-wire *a* passes under the lever through the staple or eye and has its ends secured to screw-eyes *e* at the corners of the bed at the foot thereof. Brace-wire *b* passes through the notch and has its ends secured to screw- 30 eyes *f* at the corners of the bed at the head thereof. Brace-wire *c* also passes through the notch and has its ends secured to screw hooks or eyes *g* in the railings six inches from

their center toward the head of the bed. Brace-wire *d* is placed above brace-wire *a* and 35 secured by screw hooks or eyes *h* in the railings six inches from their center toward the foot of the bed. The lever is then lifted upright while wires *b* and *c* are slipped up to the staple or eye. The lever is then pushed 40 downward toward the head of the bed, turned under wire *b*, and secured by means of brace-wire *d* being pulled over and engaging notch 3.

From the foregoing description and drawings the construction and operation of my 45 brace can be readily understood.

What I claim as new, and desire to secure by Letters Patent, is—

A bed-brace comprising the wires *a*, *b* and *c* which have their ends secured by screw eyes 50 or hooks to the head, foot and sides of the bed respectively, and connected at the center of the bed by lever 1, provided near larger end with a staple or eye and a notch; brace-wire *a* passes through the staple or eye and 55 wires *b* and *c* through the notch; when by vertical adjustment the lever is reversed, turned under wire *b* and secured by a brace-wire *d* by a notch 3 substantially as described.

In testimony whereof I have hereunto set 60 my hand in the presence of two subscribing witnesses.

HENRY LAFAYETTE BOOTH.
